UNITED STATES PATENT OFFICE.

CHARLES A. LINDSTRÖM, OF ALLEGHENY, PENNSYLVANIA, ASSIGNOR TO
PRESSED STEEL CAR COMPANY, OF PITTSBURG, PENNSYLVANIA, A
CORPORATION OF NEW JERSEY.

TRUCK-BOLSTER.

No. 832,683.

Specification of Letters Patent.

Patented Oct. 9, 1906.

Application filed January 13, 1905. Serial No. 240,910.

To all whom it may concern:

Be it known that I, CHARLES A. LINDSTRÖM, of Allegheny, Allegheny county, Pennsylvania, have invented a new and useful 5 Truck-Bolster, of which the following is a full, clear, and exact description, reference being had to the accompanying drawings, forming part of this specification, in which—

Figure 1 is a side elevation, partly broken 10 away, of my improved bolster. Fig. 2 is a cross-section on the line II II of Fig. 1, and Fig. 3 is a top plan view.

My invention relates to the class of truck-bolsters and is designed to provide an improved 15 structure of the type wherein the compression member is formed of cast metal, while the tension member is formed of wrought material.

The object of the invention is to arrange 20 the compression member so that the tension member may extend in a substantially straight line to its connecting-point, the web of the compression member being thickened for bending the end of the tension member 25 around it.

The invention further consists in the construction and arrangement of the parts, as hereinafter described and claimed.

In the drawings I show the compression 30 member of the truck-bolster, which is made of cast-iron or cast-steel with a web 2, having side flanges 3, which are deepest at the center and are gradually narrowed toward the ends. At the center the cast member is provided with a strut 4, which may be either integral with or made separate from the body 35 of the compression member.

At each end the web 2 of the compression member is inclined upwardly and provided 40 with a thickened portion 5, around which the end of the tension member 6 is bent and secured by rivets 7, extending through the thickened web and through both thicknesses of the tension member. This tension member 45 extends between the flanges of the compression member, which are extended downwardly and form guides 8 for the bolster. 9 is a separate casting, forming the spring seat or support. The side bearings 10 and the center plate 11 may be formed integral with 50 the casting or made separate from and secured thereto.

The advantages of my invention result

from the peculiar connection between the cast impression member and the wrought-plate tension member, which allows the tension member to extend in a straight line to its connecting-point and gives an easy bend, owing to the thickening of the web at the ends of the compression member. The forming of the cast flanges deeper at the center than the ends gives the greatest amount of material where the greatest stresses are carried.

I prefer to provide the cast compression member with longitudinal intermediate depending ribs 12, which will aid in preventing the web 2 from buckling under the strains. These ribs are preferably narrower than the flanges 3, as shown in Figs. 1 and 2.

Variations may be made in the form of the two members and their connection without departing from my invention.

I claim—

1. A truck-bolster having a cast compression member, whose web is formed with integrally-cast upwardly-inclined, thickened end portions, and a tension member whose end portions are bent around and secured to the said inclined portions; substantially as described.

2. A truck-bolster, having a cast compression member, formed with integrally-cast upwardly-inclined, thickened end portions, having depending bolster-guiding flanges, and a tension member extending in a substantially straight line to the said thickened portions, and bent around and secured to the same; substantially as described.

3. A truck-bolster having a cast compression member formed with flanges which are deeper at the center than at the ends, the ends having integrally-cast upwardly-inclined thickened portions; substantially as described.

4. A truck-bolster, having a cast compression member formed with depending flanges deepest at their central portion, said member having at its ends downwardly-extending flanges forming bolster-guides, and also upwardly-inclined thickened portions, and a wrought tension member secured to said thickened portions; substantially as described.

5. A truck-bolster having a cast compression member with integral end flanges ex-

tended downwardly and forming guides for the bolster and an open housing for the spring-seat, and a wrought tension member connected to the compression member; substantially as described.

6. A truck-bolster having a cast compression member with flanges deeper at the center than at the ends, and depending flange portions extending downwardly from the

ends and arranged to form guides for the bolster and an open housing for the spring-seat; substantially as described.

In testimony whereof I have hereunto set my hand.

CHARLES A. LINDSTRÖM.
